UNITED STATES PATENT OFFICE

GILES S. MOORE, OF INDIANAPOLIS, INDIANA

SLIDING TROLLEY

Application filed December 31, 1929. Serial No. 417,713.

This invention relates to a sliding trolley or shoe for electric trains and cars and an object of the invention is to provide a trolley shoe wheel which will provide a large surface contact on the trolley to prevent burning out the shoe and thus to prolong its life.

A further object is to provide a novel arrangement whereby in backing up the shoe may be kept in long line contact with the trolley.

Referring to the accompanying drawings which are made a part hereof and on which similar reference characters indicate similar parts,

Figure 1 is a side elevation showing the position of the device when the car is in forward movement,

Figure 2, a side elevation showing its position in reverse movement,

Figure 3, a longitudinal section showing portions of the shoe,

Figure 4, a section on line 4-4 of Figure 3, and

Figure 5 a perspective of the shoe showing its position when the car is moving backwards.

In the drawings numeral 10 indicates a harp which is attached to the upper end of a trolley pole. This harp has a pair of forks 11 and 12 in which a spider or frame 13 is mounted. The spider 13 is pivoted on a pin 14 and is permitted an oscillating motion which motion is limited by stops 15 and 16 on the spider which engage the harp at corresponding stops 17 and 18. A contact shoe 19 has a depending lug 20 which is pivoted at 21 to a lug 22 on a short lever 23 which is pivoted on the pin 14. The arm 22 to which the shoe is pivoted is permitted an oscillatory movement. The shoe 19 is grooved as shown at 26 to receive a trolley wire 27. When the car is traveling forward, friction in the shoe 19 will hold it to the position

shown in Figure 3. When in this position a long line surface 28 is in contact with the trolley wire. This prevents burning of the wire or of the trolley shoe. With a wheel trolley contact there is theoretical contact at only a single point on the wheel and on the

wire. This tends to burn both the wire and the wheel at starting of the car. With the long line contact furnished by my device the danger of burning the surface of the shoe and of the wire is avoided. In order to insure a good electrical contact between the shoe 19 and the harp a flexible cable 29 is secured at 30 to the shoe and at 31 to the harp. For providing contact in reverse motion of the car a contact belt 31 is mounted on rollers 32 and 33 which rollers are pivoted on pins 34 and 35 mounted in the rear of the spider 13.

In operation when going forward the harp 10 will be biased in the direction of the arrow 36 in Figure 1 to hold the shoe 19 in contact with the trolley, and friction on the shoe will hold the shoe in the rear position with the arm 22 toward the rear. When the car is reversed the shoe 19 will slide forward, at which time the spider 13 will further swing on its pivot 14 to the position shown in Figure 2. When in this position the trolley 27 will ride on the top of the belt 31. The tension of the harp 10 will still be in the direction of the arrow 36 but the reverse motion of the car will hold the spider in the position shown in Figure 2. The belt 31 provides a long line contact with the trolley 27 and provides a rolling contact as well. This not only eliminates friction but does away with the danger of burning out portions of the trolley shoe, or burning the trolley wire, such as occurred with trolleys having a single trolley wheel which may have only a point contact with the wire and with the periphery of the wheel.

It will be obvious to those skilled in the art that various changes may be made in my device without departing from the spirit of the invention and therefore I do not limit myself to what is shown in the drawings and described in the specification, but only as indicated in the appended claims.

Having thus fully described my said invention, what I claim as new and desire to secure by Letters Patent, is:

1. A sliding trolley comprising a harp, a shaft, a frame pivoted on said shaft, a link pivoted to said shaft, a sliding contact

shoe pivoted to said link and normally resting on said frame at the rear thereof when said trolley is moving in a forward direction and adapted to rock to a forward position when the said trolley is moving in the reverse direction thereby changing the center of torque to cause the frame to rotate on said shaft, substantially as set forth.

2. A sliding trolley comprising a harp, a shaft, a frame pivoted on said shaft, a link pivoted to said shaft, a sliding contact shoe pivoted to said link and adapted to sliding movement with respect to said frame to shift the center of the torque, a rolling contact member adjacent said sliding shoe and adapted to swing into contacting position by the shifting of said sliding shoe, substantially as set forth.

In witness whereof, I have hereunto set my hand and seal at Indianapolis, Indiana, this 27th day of December, A. D. nineteen hundred and twenty-nine.

GILES S. MOORE.
